UNITED STATES PATENT OFFICE.

HENRY BERRY, OF SHELTON, ASSIGNOR TO THE DERBY SILVER COMPANY,
OF DERBY, CONNECTICUT.

DESIGN FOR AN ORNAMENTAL RECEPTACLE.

SPECIFICATION forming part of Design No. 24,231, dated April 23, 1895.

Application filed March 8, 1895. Serial No. 541,049. Term of patent 7 years.

To all whom it may concern:

Be it known that I, HENRY BERRY, a citizen of the United States, residing at Shelton, in the township of Huntington, county of Fairfield, and State of Connecticut, have invented and produced a new and original Design for an Ornamental Receptacle, of which the following is a specification, reference being had to the accompanying drawing, forming a part thereof, and which illustrates in a perspective view an ornamental receptacle embodying my design.

The leading feature of my design consists in the ornamental form of the receptacle, the latter having a spheroidal outline approximating that of an egg placed on its side, and the upper surface of the receptacle, substantially near its center, having an irregular or broken

edge surrounding the opening thereto, substantially as shown in the accompanying drawing.

In the drawing, A designates the receptacle; B, the opening in the upper side and about the center thereof, and C the irregular or broken edge surrounding said opening.

The receptacle is elongated horizontally and may rest upon the feet D.

What I claim is—

The design for an ornamental receptacle, substantially as shown and described.

Signed at Shelton, Connecticut, this 5th day of March, 1895.

HENRY BERRY.
